US00D374657S

United States Patent [19]
Beranek

[11] **Patent Number:** **Des. 374,657**
[45] **Date of Patent:** ****Oct. 15, 1996**

[54] **ELECTRICAL POWER SUPPLY PLUG**

400283 4/1966 Switzerland 439/692

[75] Inventor: **Ernst Beranek**, Vienna, Austria

Primary Examiner—Joel Sincavage
Attorney, Agent, or Firm—Henry M. Feiereisen

[73] Assignee: **Egston Eggenburger System
Elektronik Ges. m.b.H.**, Eggenburg,
Austria

[57] **CLAIM**

[**] Term: **14 Years**

The ornamental design for an electrical power supply plug,
as shown and described.

[21] Appl. No.: **33,422**

DESCRIPTION

[22] Filed: **Jan. 19, 1995**

FIG. 1 is a side elevational view of an electrical power
supply plug showing my new design;

[30] **Foreign Application Priority Data**

FIG. 2 is a top view thereof;

Jul. 21, 1994 [AT] Austria 2889/94

FIG. 3 is a side elevational view thereof as seen from the
opposite side of FIG. 1;

[52] **U.S. Cl.** **D13/138; D13/133**

FIG. 4 is a front elevational view thereof;

[58] **Field of Search** **D13/137, 138,**

FIG. 5 is a top, front and side perspective view thereof;

D13/133; 439/597, 600, 606, 692, 699

FIG. 6 is a rear elevational view thereof;

[56] **References Cited**

FIG. 7 is a top, rear and side perspective view thereof;

U.S. PATENT DOCUMENTS

FIG. 8 is a bottom plan view thereof; and,

D. 178,359 7/1956 Gombar D13/138

FIG. 9 is a bottom, front and side perspective view thereof.
